MANUALLY OPERATED DIAPHRAGM PUMP

Randal Munster Eves, Bangor, and William John Brian,
Ballywalter, Northern Ireland, assignors to Munster
Simms Engineering Limited, Belfast, Northern Ireland

Filed Aug. 10, 1970, Ser. No. 24,396

Term of patent 14 years

Int. Cl. D23—01

U.S. Cl. D23—14

FIG. 1 is a front elevational view of a manually operated diaphragm pump showing our new design;

FIG. 2 is a rear elevational view;

FIG. 3 is a side elevational view;

FIG. 4 is an elevation of one end;

FIG. 5 is an elevation of the other end;

FIG. 6 is a section on the line 6—6 of FIG. 1; and

FIG. 7 is a side elevational view showing a pump arm and a diaphragm in an alternative position.

We claim:

The ornamental design for a manually operated diaphragm pump, substantially as shown.
